UNITED STATES PATENT OFFICE.

EMILE RIMAILHO, OF PARIS, FRANCE, ASSIGNOR TO CAMPAGNIE DES FORGES ET ACIERIES DE LA MARINE ET D'HOMECOURT, OF PARIS, FRANCE.

TRAVELING LOCK FOR GUN CARRIAGES.

Application filed March 21, 1924, Serial No. 700,920, and in France April 24, 1923.

For gun carriages having a large range and provided with a quadrilateral support on the ground composed of two wheels and two spades, one of the means employed in order that the said quadrilateral support may be adapted to the ground consists in pivoting the vehicle axle to the carriage by means of a longitudinal spindle. Suitable locking means must be provided for the pivot 10 in conditions of travel.

When the said carriage is provided with an elastic suspension device for road travel, consisting for example of plate springs or like elastic means interposed between the carriage and the axle, it is necessary to provide locking means in order that the suspension parts shall not be subjected to the firing shocks.

The present invention has for its object to provide an arrangement whereby the locking may be obtained in either of the above-mentioned cases by the operation of a single common control device in either direction, exclusive of all other operations, and chiefly 25 without being obliged to raise the said carriage in order to provide for the expansion of the elastic parts of the suspension.

The said arrangement comprises locking elements and a control for actuating the said elements. When the control is operated in a given direction, it brings the locking elements into the firing position; the lateral inclination is left free while the vertical motion is prevented by the said locking 35 means. By operating the control in the contrary direction, the locking devices are brought into the position for road travel; the lateral inclination is now prevented, while the vertical motion is released.

The appended drawings show by way of example which is no wise limitative, two embodiments of the said invention.

Fig. 1 is a front elevational view of the first form of construction, the carriage being reduced to its cross-piece.

Figs. 2 and 3 are cross-sections on the lines A—A and B—B of Fig. 1 respectively.

Fig. 4 is an elevational view of the same device with the spring removed, and Fig. 5 is a vertical section on the line C—C of Fig. 2.

Figs. 6 and 7 are views analogous to Fig. 4, showing the elements in their different positions.

Figs. 8 and 9 are views analogous to Figs.

1 and 7, relate to the second form of the device, with the spring removed.

Fig. 10 is a section on the line D—D of Fig. 9.

In the first form of construction, the locking device consists of two wedges 1 which are slideable on the axle 2 by means of a control screw 3 having two threads in contrary directions, each thread being engaged with corresponding threads formed in the 60 said plates; the said screw is rotated for instance by a ratchet lever or a handle 4. At the middle part of the axle 2 are two extensions 5 serving as supports and guides for the said wedges.

The wedges may be moved apart or may be brought together until they are in contact; when in contact, their upper surfaces coincide so as to form a cylindrical surface of revolution 6 whose centre line is the longitudinal pivoting axis. The cross-piece 7 of the carriage has a corresponding cylindrical surface 8 whereby the carriage is caused to bear upon the axle for the firing operation, and one of these elements can be laterally inclined with reference to the other. Upon the said cross-piece is revolute an axle 9 which constitutes the longitudinal pivot and to which are secured at the middle part two transverse plate springs 10 and 11 whose 75 ends are attached to the vehicle axle by shackles; on the axle 9 is also revolute a retaining strap 12 extending below the said wedges when in the firing position and preventing the cross-piece 7 from being raised 80 from the vehicle axle. The said cross-piece is provided with two pairs of downwardly extending lugs 13 having thereon the rollers 14 with which the said wedges may co-operate 85 when moved apart.

In this position of the wedges, the surface 8 of the cross-piece is allowed to descend, passing between the said plates which prevent any movement of inclination of the carriage relative to the axle.

The control rod for the said wedges passes through the centre of the vehicle axle and is connected to the same in an elastic manner by means of the springs 15, whereby all jar-ring motion between the rollers and wedges 100 is obviated when in the position of travel.

In the second form of construction, Figs. 8, 9 and 10, the plate suspension springs 10 and 11, which are attached to the axle 2 by shackles, are fitted at the middle part into 105

the members 16 which comprise an extension 17 and are traversed by a longitudinal axle 9. To the latter are pivoted on the one hand the cross-piece 7 of the carriage and on the other hand two pairs of bent arms 18 whose ends 19 can be maintained either in the adjacent or separated position for instance by means of a rod with double screw-thread 20 which is turned by a handle or a ratchet lever 4 and the rod and link gear 21 which is properly jointed and slideable.

When in the separated position, the two pairs of arms are held in two cut-out portions 22 of the vehicle axle, thereby locking the suspension by connecting the vehicle axle with the pivoting axle 9. In this event the carriage can be inclined laterally with reference to the vehicle axle by pivoting on the axle 9.

20 When moved together, the two pairs of arms come into contact with the extensions 17 of the members 16 whilst their ends 23 hold the cross-piece 7, so that the said arms and the cross-piece become secured to the members 16 into which the vehicle springs are fitted.

The carriage is thus suspended from the axle in an elastic manner and can no longer pivot upon the axle 9.

30 Claims:

1. In a field gun with wide range, the combination of a carriage, an axle, an elastic

suspension between the said axle and the said carriage, a longitudinal pivot about which the said carriage can turn relatively 35 to the said axle, and a common mechanism for locking the said elastic suspension and for locking the carriage upon its pivot, said mechanism being adapted to allow of locking the elastic suspension at same time as 40 the unlocking of the carriage upon the longitudinal pivot, or the unlocking of the suspension at same time as the locking of the carriage upon this pivot.

2. In a field cannon having a great firing 45 range, the combination of an axle, transverse plate springs pivoted at the ends to the said axle, a longitudinal shaft mounted at the middle of the said springs, a gun carriage pivoted upon the said shaft, movable elements which act in their first position to permit the rotation of the carriage on the said longitudinal shaft while preventing all vertical motion thereof relatively to the said axle, and in the second position to prevent 50 all rotation of the gun carriage on the said shaft while permitting the ascent of the carriage relatively to the said axle, and a control rod with right and left hand screw-thread which is screwed upon the said elements and serves to change their position.

In testimony that I claim the foregoing as my invention, I have signed my name.

EMILE RIMAILHO.
